UNITED STATES PATENT OFFICE.

FRANK A. BRACKETT, OF MANCHESTER, NEW HAMPSHIRE, ASSIGNOR TO W. H. McELWAIN COMPANY, OF BOSTON, MASSACHUSETTS, A CORPORATION OF MASSACHUSETTS.

CONSTANT-PRESSURE PRESS.

Application filed January 3, 1920. Serial No. 349,300.

To all whom it may concern:

Be it known that I, FRANK A. BRACKETT, a citizen of the United States, residing at Manchester, in the county of Hillsborough and State of New Hampshire, have invented new and useful Improvements in a Constant-Pressure Press, of which the following is a specification.

It is the purpose of this invention to furnish a machine for pressing a collection or pile of articles, at the same time providing means by which other articles may be applied to the pile or collection without requiring or occasioning any substantial slackening of the pressure.

One of the uses for which such a machine is particularly designed and adapted is that of holding under pressure cemented and doubled shoe soles, that is, soles which are made of two or more layers adhesively united together, although this statement is not intended and is not to be construed as in any sort a limitation of the utility of the invention or of the scope for which I claim protection for the same; but, explaining the nature of the invention by reference to this particular use as a concrete instance, I would say that, it is important that pressure should be applied to the doubled layers as soon as possible after they have been cemented and laid together, that the pressure should be continued without substantial intermission until the adhesive has set or dried enough to be secure, and that economical operation requires that a large number of soles or other articles operated upon should be held under pressure at the same time in the same machine. The practice generally followed in shoe factories in making doubled soles is to cement and assemble together the constituent layers of a considerable number of such soles before any are put under pressure; that is, an operator will cement and double a number of soles in succession until he has accumulated a pile, when he will place the pile in the press, or put it in condition to be carried away and pressed. This is the most economical procedure heretofore devised for this sort of work, but it has certain incidental disadvantages, among which is this: that, while the soles first cemented are awaiting the accumulation of a pile large enough to be handled, the cement commences to dry, and this partial drying

makes it impossible to obtain a perfect bond when the drying afterwards continues under pressure. To retard the setting of the cement in this manner, the practice has obtained of making the cement excessively thick and tacky, so that it will dry only slowly, but this results in the use of much more cement than is actually needed for the ultimate purpose of effecting proper adhesion, and also requires more time after the soles have been put in the press for complete drying and setting.

Being acquainted with the processes heretofore used and aware of their shortcomings, I have designed a machine which is effective to hold a single cemented sole or a pile of any number of soles, within reasonable limits; to apply pressure to such sole or pile; and to permit the addition of more soles on top of the pile, without any substantial relaxation of the pressure already acting on the pile. This machine forms the subject of the present invention, and, together with all modifications in structure and use which in principle and in the essential character of function and result embody the invention, is the subject for which I claim protection, and is hereinafter recited in the appended claims.

The machine which I have chosen to illustrate and describe in detail in this specification for explanation, is a press particularly designed for the special purpose of putting and holding cemented and doubled shoe soles under pressure, wherefore in this description I shall generally refer to the invention as a machine for that purpose, and to the work operated on as shoe soles, but without intending or implying any limitation in the scope of the protection herein claimed.

Referring now to the drawings:

Figure 1 shows a side elevation of the specific sole press above referred to.

Figure 2 is a front elevation of the press.

Figures 3 and 4 show in side elevation a detail of the machine, in two respectively different positions; this detail being an indicator, to give warning when the pile of soles has been built up to a predetermined height.

Figure 5 is a vertical section on line 5—5 of Figure 3.

Figure 6 is a front elevation of the indicator referred to.

Figure 7 is a sectional plan view of the press, representing parts below the line 7—7 of Figures 1 and 2.

Figure 8 is a longitudinal section taken 5 on the line 8—8 of Figure 7.

Figure 9 is a cross section taken on line 9—9 of Figure 8.

Figure 10 is a front elevation of a detail.

Figures 11 and 12 are fragmentary views 10 showing the holder for the pile of soles, with the pile thereon, and an illustration of the means provided for securing the pile to maintain the pressure after its removal from the press.

Figure 13 is a plan, on an enlarged scale, 15 of the parts below the line 13—13 of Figures 1 and 2.

Figure 14 is a vertical longitudinal section 20 of the mechanism shown in Figure 13, being taken on the line 14—14 of said figure.

Figure 15 is a detail of the mechanism shown in Fig. 14.

Figure 16 is a cross section, enlarged, of 25 a starting and stopping means forming part of the particular combination illustrated in Figure 15.

Figures 17 and 18 are views similar to 30 Figures 15 and 16, respectively, of the same stop motion in a different position.

Figure 19 is a longitudinal section of the clutch which forms a part of this mechanism.

Like reference characters indicate the 35 same parts in all of the figures.

Describing now the machine thus illustrated, 21 represents the base, from which rise two bars 22 and 23, and two rods 24 and 25, all supporting and securing a head

40 26. The base, bars, rods, and head thus described provide a rigid frame, whereon the movable parts are supported. Said bars are likewise guides, whereon a carriage 27 is adapted to slide up and down, said carriage having shoes, 28 and 29, which bear against the bars. The carriage has also an arm 30, projecting rearward, to which is connected a rope or a chain 31, passing over guide pulleys 32, and suspending 45 a counterbalance weight 33. The pulleys are supported by a bracket 34 on the head. The bars 22 and 23 are provided with teeth 35, and in mesh with these teeth are pinions 36 and 37, affixed to a shaft 38, rotatable in bearings carried by the carriage 27. The shaft 38 also carries a brake drum 39, which is surrounded by a brake band 40. This brake band may be a flexible or springy steel strip, having a facing of leather or equivalent friction-causing material, as is common in brake constructions, and one end of it is connected to a stud 41, mounted on the carriage, as shown in Figure 1. The carriage also supports a second 50 stud 42, on which there is pivoted a lever

43, having as its short arm an adjustable screw 44 in a lug at one side of the lever, while its long arm is provided with a cam or wiper surface 45, adapted to be engaged by a finger 46 on the locking piece 47, 70 which is pivoted upon the shaft 38, and has an operating handle 48. The opposite end of the brake band from that which is attached to the stud 41 as above described, carries a lug 49, which is engaged by the 75 screw 44 or short arm of lever 43. Thus, when the lock device is placed as shown in Figure 1, where the finger 46 has pressed against and ridden along the cam surface 45 up to the stop shoulder at the end of 80 that surface, the brake band is tightened about the brake drum, and the lock is secured so as to maintain this condition, by being across the dead center, or, if desired, by a slight depression in the cam surface 85 which it enters.

By this means resistance is opposed to rotation of shaft 38, and therefore to descent of the carriage 27. This carriage is provided to support the soles being pressed, 90 and the resistance to its movement afforded by the brake determines the intensity of the pressure which can be applied by the pressing means about to be described. This resistance may be relaxed easily enough by 95 turning the locking device in counter-clock-wise rotation with respect to Figure 1 (in other words, by pulling the handle 48 forward). The counterbalance weight acts to return the carriage to its raised position 100 after a pile of soles has been removed from it and the brake has been released, whereby to relieve the operator of unnecessary labor.

For holding the soles being pressed, there 105 are provided a number of removable bottom plates or holders, of which one is shown in Figures 7 to 12. Each of these holders comprises a base 50, conveniently made as a casting, and having sockets 51 at suitable locations, and a supporting plate 52. The latter is made of flat stock, with a sufficiently smooth upper surface, and having stiffness enough to retain its flat condition under the conditions of use or abuse which it may 110 meet: and it rests upon springs 53, contained in the sockets 51, there being enough of these springs and sockets, properly arranged, to give the plate a stable and resilient support. When this holder is placed on the carriage 115 27, as shown in Figures 8 and 9, the plate 52 provides the actual work-supporting element or surface of the press. It is removable with the stack of soles at the end of one cycle of the machine, making way for substitution of a similar holder. The holder is equipped with means for retaining the supported accumulation of soles under pressure, even after removal from the press, such means being, in the construction shown, a 120 125 130

chain 53^a, which is permanently connected at one end to the holder by an eye 54 at one side of the base, and is adapted to be passed over the pile of soles and down on the other side, and to be detachably secured to a hook 55, also mounted in the base of the holder.

The presser for applying pressure to the work pieces on the holder is here shown as a plate 56, having a flat under surface of sufficient area to apply and distribute the required pressure to such work pieces, and having a hinged section 57, mounted by a horizontal pintle 58, for a purpose presently to be described. This presser is secured to the lower end of the rod 59, and the hinged section is braced by a strut 60, pivoted to it and bearing on the shoulder 61 at the side of the rod 59. The rod 59 slides endwise through an upright guideway in the head 26, and it is secured to a crosshead 62, which is secured upon the ends of two upright rods 63 and 64, and is supported by springs 65 surrounding said rods and bearing on the head 26. The rods 63 and 64 pass through guideways in the head 26, and also through guideways in the carriage 27, and are fastened at their lower ends to a crosshead 66, which latter is connected by a link 67 with a lever 68. Said lever has its fulcrum on a pin 69, secured in any suitable way in the base 21, and it is operated by a cam 70, which bears upon a trudle-roll 71 carried by the lever.

Cam 70 is on a cam shaft 72, which is driven from the main shaft 73 by a pinion 74 on the latter, and a gear 75 on the shaft 72, the directions of rotation of these shafts being as indicated by arrows in Figure 14. A belt pulley 76 is loosely mounted on the shaft 73 for giving motion thereto, and is adapted to be connected therewith and disconnected therefrom by a start and stop clutch mechanism later described.

The cam shaft 72 carries a second cam 77, which acts upon a roll or stud 78 carried by one arm of a lever 79, which is loosely pivoted on shaft 73, and has a second arm 79^a pivoted at 80 to an endwise-movable rod 81, said rod rising at the rear of the machine, as shown in Figure 1. On its upper end the rod 81 carries a rack bar 82, which is held by a guide 83 at the rear of the head 26, and has teeth on each of its opposite sides (Fig. 9). These teeth engage toothed arms or segments 84, 84, attached to rock shafts 85, 85, which have proper bearings in the head 26. These rock shafts carry pressers 87, 87, the function of which is to bear against the soles and maintain pressure thereon when the presser 56 is raised. For convenience of description, I will hereafter call the presser 56 the main or holding presser, and the pressers 87 the secondary pressers. The latter are adapted to assume the spread-apart position shown in Figures 2

and 12, when the rack bar 82 is lowered, and to take the closed-in position shown in Figures 7 and 9 when said rack bar is raised. A spring 88 is connected to the pin 80 and to the fixed upper head, and is thereby caused to exert constant pressure upwardly upon the rack bar, tending always to close in the secondary pressers, except when the latter are spread apart by the more powerful and positive action of the cam 77.

It will be apparent from Figure 14 that cam 70 is formed with a rise from its lowest point *b* to the point *c*, with a dwell from *c* to *d*, with a rise from *d* to *e*, a further dwell from *e* to *f*, and a descent from *f* to *b*. When the machine is at rest, and also at the end of each cycle of its normal operation, the low point *b* of cam 70 is beside the roll 71; and the low part of cam 77 is beside the stud 78; the main presser being then in its raised position and the secondary pressers in their positions of nearest approach to one another whereby they are adapted to bear on the work. Cam 77 is so formed and arranged with respect to cam 70 that it causes displacement of the secondary pressers into their spread apart, inoperative positions after the main presser has begun to move toward the pile of work, and holds the displaced secondary pressers until the highest part of cam 70 has come into action to advance the main presser to the limit of its pressing movement.

The chief operations of the machine will now be explained, starting with the assumption that the machine is in the position of rest and that the carriage 27, with an empty holder 50 placed upon it, is at the upper limit of its path, where it is arrested by the secondary pressers. These pressers are provided with work-engaging under surfaces adapted to bear on the side parts of the work pieces, when the pressers are in their operative positions, and are offset outwardly to leave between them and directly above the parts which have such surfaces, an open space wide enough to admit insertion of a work piece under the raised main presser. The preferred construction of secondary pressers for the particular uses of the machine here described is shown in Figures 7 and 9; and attention is called to the fact that in Figure 9 two work pieces *a* (doubled soles) are shown as resting on the work support and being clamped thereon by the secondary pressers, while a third work piece *a'* is shown as having been slipped over the secondary pressers and beneath the raised main presser. Now, when the controller for the starting and stopping clutch (in this machine a treadle 89) is depressed, the cam shaft is set in rotation, with the effect of bringing the main presser down on the work piece *a'* thus placed, and of spreading the secondary pressers, these ac-

tions being in such sequence that pressure is applied by the main presser to the whole accumulation of work pieces before, or at least not after, removal of the secondary 5 pressers from operative position, and that the latter move aside quickly thereafter to clear the side edges of the newly added work piece a' . Continuation of the downward movement of the main presser first compresses the springs 53 of the holder, and then forces the entire work support downward against the resistance offered by the brake 40, whereby a predetermined degree of pressure is applied to the work piece. There- 10 after, when the work piece last put in place has passed across the path of the secondary pressers, the latter are moved inward to their previous positions. Finally with the completion of the cycle (which involves one complete rotation of the cam shaft 72), the main presser is raised clear of the last placed work piece, but the latter and all those beneath it are retained under pressure by the secondary pressers.

25 In this action, the resilient work holder performs an important function, because it causes delay in the downward displacement of the carriage until the springs 53 have been compressed a certain amount; where- 30 by, first, the compression of said springs allows the edge of the work piece to be carried far enough below the secondary pressers to avoid interference with the latter; and then, their resilience causes the pile to 35 be lifted, when the main presser rises, and held against the secondary pressers with the force due to the initial compression of the springs, which may be nearly as great as that applied by the main presser. Thus, 40 the springs 53 provided for such play or relative motion between the carriage and the work supporting element thereof (plate 52), under substantially constant pressure, as is needed to avoid interference between the 45 piece last added to the pile and the secondary pressers. Such play or movement need not be great, but must be enough to compensate for possible bending or warped condition of the work piece.

50 I have provided a gage device for centrally locating the work pieces as they are successively placed upon the pile, so that they will clear the secondary pressers properly and also will be properly pressed upon 55 by the latter, and to insure that the successive work pieces will be correctly enough aligned in the pile to avoid building up a slanting or crooked pile, a defect which might cause collapse in the case of work 60 pieces, such as shoe soles, which have comparatively slight width in proportion to the height to which the pile is built. This gage is shown in Figures 7, 8, 9, and 10, and it comprises an end stop 90, and resilient cen- 65 tering arms 91, 92. Said end stop is se-

cured to a block 93, which slides in a guideway 94 in the under side of a plate 95, and the plate has a dovetail rib 97, fitting a guideway in a fixed lug 98 on a part of the machine head 26. A locking pin 99, spring-pressed and manually releasable (as shown in Figure 8), is provided for locking the entire gage in a manner permitting it to be removed and others to be substituted. Attached to the plate 95 are two pivot-pins 100, on each of which is mounted a hub 101, having an arm 102, and each of said arms carrying a pin 103, which projects into a transverse groove 104 on the under side of the slide block 93, as shown best in Figures 7 and 8. The side gaging arms 91 and 92 are each secured to one of the two hubs 101. A work piece, when inserted into the press, is moved onward by the operator until its end passes between the arms 91 and 92, and brings up against the stop 90. If the side arms should be spread wider apart than the width of the piece, the latter is further moved, advancing the stop 90 with it until stopped by the side gages striking the sides of the work piece. Movement of the block 93, of course, swings the side gages by the pin and slot connection just described. By this means it is insured that all soles applied to the pile are approximately centrally aligned thereon.

This procedure is repeated whenever the workman or attendant has applied a coating of cement to a sole and laid another sole, (or a tap or doubler of whatever size, material or thickness,) against this cemented surface,—that is, every few seconds,—and at each operation a sole is added to the stack and put under pressure without waste of time and without relaxing the pressure already exerted on the stack. It makes no difference what the thickness of the sole or other work piece may be, or whether such work pieces are applied singly, or two or more at a time, except that it is not possible to apply a number of work pieces having a combined greater thickness than the space between the main presser, when raised, and the adjacent operative parts of the secondary pressers. Whatever may be the thickness of the work piece capable of being inserted, the main presser applies the same pressure, and moves the work support and pieces thereon far enough to clear the secondary pressers.

When a predetermined number of the soles have been thus built into a stack or pile (that is, when the pile has been built to a prescribed height), a signal is automatically given to the operator, warning him that it is now time to remove the pile. Such signal is given by a visible indicator 105, conveniently in the form of a metal flag or target, supported at the front side of the head 26, where it is conspicuously before the eyes of

the operator, on a rock shaft 106. The latter carries an arm 107 close to the left-hand side of the head, to which is pivoted a latch 108, and to the latch is connected a spring 109, which is also connected with a link 110 pivoted to the latch at 111 and having a slot 112, which embraces and is guided on a fixed pin 113. The effort of the spring is to pull the link 110 into an approach to coincidence with the latch, or, in other words, to diminish the angle between the link and the latch, and therefore to tend to bring the device into the position shown in Figure 4, and to hold it in that position. The link 110 prevents the latch from hanging down loose and inoperative from the arm 107. A spring 114 (Figure 6) surrounds the rock shaft 106, and is secured thereto at one end in any suitable manner, while its other end, shown at 115, bears against the indicator 105, which latter is loosely mounted on the rock shaft, with ability to turn thereon. A rod 116 is mounted in an upright position beside the bar 22, in guides 117, wherein it 25 is adapted to slide endwise, and it is normally raised by a spring 118, pressing against the lower guide 117 and against a collar 119 fixed to the rod, which collar has an arm 120, passing through a slot in the bar 22 beneath the slide 27, as shown in Figure 5. This arm, coming in contact with the upper end of the slot, limits the upward movement of the rod, and, when the rod is in its uppermost position, a toe or shoulder 30 121 on its upper end overlies the latch 108, holding the target in the upright position shown in Figures 1, 2, 3, and 6.

Now, when the carriage in its descent arrives at the arm 120, it pushes the rod 116 downward until the shoulder has displaced and passed from over the end of the latch 108, as shown by dotted lines in Figure 3. At this time the arm 107 and rock shaft 106 turn relatively to the signal 105, the latter 45 being restrained from turning by the adjacent stationary head, and spring 109 being stretched; and, upon the shoulder passing off from the latch, the spring causes this arm to be suddenly raised and permits the target to fall forward, link 110 then sliding along the fixed pin 115, and being caused by the spring 109 to remain in that position.

The operator is thus notified that a large enough number of soles has been placed 50 on the pile, and he then stops the machine in the position shown in Figure 2, where the holding presses are moved aside to clear the pile, and the main presser is pressed down on top of the pile. This is not the 55 normal stopping position of the machine, but is one taken to allow the binder 53^a to be passed around the pile. It should be noted, however, that, before thus stopping the machine, the operator first lays a rigid retainer plate 122 (Fig. 11) on top of the

pile, this plate being used for the purpose of protecting the soles from injury by the binder chain and of distributing the pressure of the binder over substantially the whole area of the pile, instead of concentrating such pressure at the line where the chain passes over it. That is, a stiff retainer plate is used for the purposes indicated when the work pieces are, like soles, more or less soft and flexible, or are liable 70 to be injured by a tightly drawn binder.

The machine having been stopped in the position indicated, the binder chain 53^a, with which each holder base is equipped, is passed over the pile and drawn tight, and the nearest link is engaged with the hook 55. At this time the pivoted section 57 of the presser plate is raised clear of the pile, as shown in Figures 11 and 12, in order to permit thus passing the chain around substantially the middle of the pile. It will be seen, therefore, that the pivoted section of the presser is a means for enabling this thing to be done, and also for applying pressure over that same part of the pile. Any 80 slack existing in the chain may be taken up by driving wedges between it and any part of the pile. Then the brake 40 is relaxed and the carriage lowered to clear the presser plate, and the assembled pile, including the 85 holder, is removed and set aside, to remain under compression until the adhesive has sufficiently set. Of course, the chain or binder maintains the pressure which was 90 previously imposed by the presser, and the 95 spring compression of the holder or base causes the pressure to continue without substantial reduction, even though some slack should have been left in the chain before 100 relieving the pile from the presser.

The carriage is then raised, and the brake set, the pressing means brought back to normal position, and the operation resumed to build and press another pile of soles.

The means for stopping the machine at 105 will, either in the normal position where the secondary or retaining presses bear on the work and the main presser is raised, or in the final position where the secondary presses are relieved but the main presser bears 110 on the pile, is an important feature of the machine, which I desire to protect in the broadest possible scope. To explain this feature, I will direct attention particularly to Figures 13 to 19. The main shaft 73 is 115 driven by a pulley 76, as already mentioned, and this pulley is loosely mounted on the shaft, but is adapted to be coupled thereto by a roller clutch, consisting of rollers 123 interposed between the sleeve 124, which is 120 keyed to the shaft, and the hub 125 of the pulley. The actual contact between the rollers and the pulley hub is made through a bushing or liner 126, fixed within the pulley hub, and provided simply for the pur- 125 130

pose of furnishing a sufficiently small, hard and wear-resisting surface to co-operate with the rollers. The latter are positioned and shifted so as to effect coupling and uncoupling by a cage 127, made as a sleeve loosely contained in the annular space between the pulley hub and the shaft sleeve 124, and in which there are slots, occupied by the rollers, as shown clearly in Figures 16 and 18. On this cage there is a flange 128, abutting against a head 129 secured to the shaft, and in the face of said flange is a recess 130, containing a spring 131, and into which projects a lug or stud 132 from the head 129, as shown by dotted lines in Figures 16, 18 and 19. The spring, by exerting pressure between the stud 132 and the remote end of the recess 131, tends to shift the cage into the position shown in Figure 16, wherein the rollers are wedged into clutching contact with the shaft sleeve and the pulley hub. On the exterior of the flange 128 is a stop shoulder 133, which is arrested by a stop finger 134 to uncouple the clutch and stop the machine.

The stop finger 134 is pivoted on an arm 135 secured to a rock shaft 136, to which also is secured the control treadle or lever 89, previously mentioned. Connection between the finger 134 and arm 135 is made by a pivot pin 137, which permits the finger to swing backward, that is, to the left with respect to Figures 14, 15 and 17; while on the finger and arm are complementary abutment shoulders, preventing the finger from swinging forward when in alignment with the arm, and a spring 138 is connected to the finger and arm, being arranged and acting to hold the shoulders in contact. A link 139, connected to the finger by a pivot 140 at one side of the coupling pivot 137, is adapted to slide endwise with respect to a stud 141, and to be limited as to its range of movement by an abutment 142. The stud is fixed in position by being mounted on a conveniently accessible part of the stationary frame, and preferably the link is slotted to embrace the stud, and so to be engaged with it securely enough. The abutment 142 is conveniently provided by a screw, threaded into the rear end of the link, and adapted to be adjusted toward and away from the stud, as shown by dotted lines in Figures 15 and 17.

On the shaft 72 is secured a cam 143, which controls an arm 144 on the rock shaft 136. This arm may be a part of the treadle lever 89, as here shown, or it may be otherwise mounted on the rock shaft. Arm 144 carries a roll 145, which bears on the rim of cam 143, the latter having its high part,—that is, the part of its circumference more remote from the center,—extending through more than a semi-circumference. Actually, as represented

here, the high part extends from the point *g* around in the direction opposite to the arrow as far as the point *h*, but it is not necessary that its extent be so great.

Figure 17 shows the condition when the machine is at rest, the clutch controller being then arrested by the end of the stop finger 134, and the roll 145 being then against the low part of the cam, there being a spring 146 connected to the lever 89 and to a fixed part 147 of the framing to hold these parts in the positions described, and to tend constantly to return them to these positions when displaced. Now, if the treadle lever is moved downward, the stop finger 134 is disengaged from the stop shoulder 133, allowing the clutch to become connected. Immediately then the shaft 73 is set in rotation, and the cam 143 is also rotated by the geared connection between the two shafts, whereby the high part of the cam is placed beside the stud on arm 144, holding the arms displaced in the positions shown in Figure 15, and making it unnecessary for the operator to continue to apply pressure to the treadle lever. Spring 138 is powerful enough to prevent the toggle, which is provided by the finger 134 and arm 135, from breaking at the knuckle 137, whereby this toggle device moves as a unit clear of the shoulder 133 and until arrested by the abutment 142 bringing up against the stud 141. Thereupon the machine continues to run until the low part of the cam beyond the point *h*, arriving beside roll 145, allows the stop finger to arrest the stop shoulder 133. As the shafts 73 and 72 are geared together in a two to one ratio, the shaft 73 makes two rotations and shaft 72 a complete rotation before being thus stopped. This carries out one complete operating cycle of the pressing means.

It is necessary to stop the machine in the middle of the cycle, as already explained, when the time comes for binding the bundle of soles, and in order to stop it then, the treadle is still further depressed, or, in other words, the treadle lever is moved still further in the first direction, and thereby the arm 135 is moved beyond the point in which it is arrested by the link 139. Force being then applied to the treadle great enough to overcome the spring 138, the toggle device is bent at the knuckle, and the stop finger is turned around pivot 140 as a fulcrum, until its tip is brought into the path of stop shoulder 133, and thereby the shaft 73 is allowed to turn through only one complete rotation, and the machine is stopped when only half of the cycle has been completed. Of course, the cams for controlling the pressers are so constructed and timed that the secondary pressers are disengaged and the main presser is engaged with the arm at this time. Thus, by moving

the control treadle to a part only of its full range of movement, the machine may be caused to make a complete cycle, while by moving it through the whole of its range the machine makes only a partial rotation. Of course, it is understood that the action of spring 130 on the clutch is so rapid that the shoulder 133 is carried past the end of the stop finger immediately the latter has been displaced from the shoulder in the full movement of the treadle, whereby, even though this movement be carried out to the end without interruption, the stop finger will not be returned against the clutch controller in a position to obstruct that shoulder. Figure 14 shows the parts in the position where the machine is stopped in mid-cycle.

Having now described and illustrated, in sufficiently full detail to enable others skilled in the art to make and use the same, a satisfactory operative machine embodying my invention, I would state that I do not limit the protection which I claim to the details of that particular machine, but that I claim as my invention the essential principle of the machine embodied in any construction, however superficially diverse from that here shown, which accomplishes essentially the same results in substantially the same way.

In the operation of the machine, the holder for the pile of soles, with its spring-pressed surface plate, serves a most important function in that, after the pile has been depressed clear of the secondary pressers, it forces the pile against such secondary pressers with substantially undiminished pressure; and, further that, being under resilient compression when the binder is passed around the pile, it maintains pressure in the soles after their removal from the machine.

Wherever, in the foregoing description, I have used terms indicating direction or relative position, I have done so for the purpose only of clear and concise description of this particular embodiment of the invention, and without intent to limit the scope of my protection. The term "front" as here used means the side of the machine at which the operator stands, and that is at the right of Figure 1. This machine is designed as an upright one, to take the work pieces in a vertical pile, but the same principles may be equally well applied to an inclined or a horizontal machine, wherein the work pieces are supported or guided in a series.

The use of the machine in shoe factories, as an aid to the making of doubled or cemented soles,—to mention only one of its possible uses,—effects large economies in saving of time to the workman, in the quantity of product turned out by the workman, and in the quantity of adhesive used. Since the cemented article is put under pressure as soon as it is cemented, a thin, quick-dry-

ing adhesive may be used, and in which only as much of the adhesive principle need be included as is necessary to make the bond; and it may be applied to the work pieces in a thin layer, without any excess.

Having now explained the principles of my invention, and described an embodiment thereof in one specific machine, although without having attempted to describe all the structures in which the invention may be embodied or all the modes of its use, I declare that what I claim and desire to secure by Letters Patent is:

1. A pressing machine for cemented articles, comprising a support, a holder detachably mounted on said support and adapted to receive a series of such articles, and means for applying pressure to such series of articles, said holder having a resiliently mounted work-engaging surface adapted to yield under the pressure applied to the articles.

2. In a pressing machine, a carriage, a guide, a toothed element extending along the guide, a gear carried by the carriage meshing with such toothed element, a brake associated with the gear to oppose frictional resistance to rotation thereof and thereby to yieldingly resist travel of the carriage, said carriage being adapted to support a series of articles to be compressed, and means for applying pressure to such articles.

3. In a pressing machine, the combination with a presser and means for moving the same back and forth in a given path, of a secondary presser at one side of said path, consisting of a pivoted arm and a pressing jaw movable toward and away from said path, and means for so moving the secondary presser, comprising a gear segment connected thereto and an operating gear element meshing with said segment.

4. In a press machine a work holder adapted to hold a series of articles under pressure and comprising a base, a work-engaging plate, and springs connecting said plate and base and permitting yieldingly resisted movement of the former toward the latter.

5. In a press machine a work holder adapted to hold a series of articles under pressure and comprising a base, a work-engaging plate, springs connecting said plate and base and permitting yieldingly resisted movement of the former toward the latter, and means on said base for attachment of a binder passed about a pile of articles placed on the plate to hold such articles under pressure applied by said springs.

6. In a press machine a work holder adapted to hold a series of articles under pressure and comprising a base, a work-engaging plate, springs connecting said plate and base and permitting yieldingly resisted movement of the former toward the latter, a flexible binder permanently attached to

one side of said holder base and adapted to be passed over a pile of articles placed on the holder plate, and fastening means at the opposite side of the base for securing the binder when so placed.

7. In a press machine a work holder adapted to hold a series of articles under pressure and comprising a base, a work-engaging plate, springs connecting said plate and base and permitting yieldingly resisted movement of the former toward the latter, a flexible binder permanently attached at one of its ends to said base and adapted to be passed around a pile of articles bearing against the plate, and means for securing the binder so placed whereby to maintain the articles under pressure of the springs.

8. A press machine adapted to hold a pile of cemented articles under pressure and to apply pressure to articles successively added to the pile, comprising a work support, a back and forth moving presser for applying pressure intermittently to articles placed in a series on said support, means for so moving said presser, a retainer and means for operating it intermittently to retain said articles under pressure when said presser is withdrawn, said presser and retainer being constructed to permit insertion between them of articles added to the pile, and centering means arranged to aline articles so added with those to which pressure has already been applied.

9. A press machine comprising a presser movable back and forth, a work support movable in the line of pressure application of said presser, yielding means resisting movement of said work support, retaining means adapted to hold under pressure articles upon which said presser has previously been pressed, being constructed and located to provide a space for the reception of additional articles when the presser is moved away from the work support, and centering means flanking the space so provided adapted to aline the articles inserted in said space with those previously pressed upon.

10. A press machine comprising a presser movable back and forth, a work support movable in the line of pressure application of said presser, yielding means resisting movement of said work support, retaining means adapted to hold under pressure articles upon which said presser has previously been pressed, being constructed and located to provide a space for the reception of additional articles when the presser is moved away from the work support, and centering means comprising a stop at the back of such space adapted to be struck by an article inserted into the space and being movable in the direction of insertion of such article, and side gaging arms at opposite sides of the space connected with and actuated by said stop to move toward the middle of the space

when the inserted article presses on the stop.

11. The combination of pressing means operable intermittently to apply pressure to articles successively added to a series, and centering means for alining such articles with said series comprising separated gaging members, a stop located and movable in a line between said gaging members, and connections between said stop and gaging members operable to move said members toward each other when the stop is moved in one direction.

12. A centering mechanism comprising separated gaging members, a stop located and movable in a line between said members, and connections between said stop and members arranged to shift the members oppositely to one another when the stop is moved.

13. A centering mechanism comprising separated pivotally mounted gaging arms, a stop movable in a line between said arms, and actuating arms secured to said gaging arms projecting respectively from the latter to the stop and having a sliding connection therewith, whereby when the stop is moved the gaging arms are likewise moved oppositely to one another.

14. In a press machine having a supporting frame, an adjustable centering device consisting of a plate, a stop member slidingly mounted upon said plate, side gaging arms pivoted to said plate, and connections between said stop member and gaging arms, constructed to transmit simultaneous movement to the gaging arms from movement of the stop, said plate having means for detachable connection with the machine frame.

15. In a press machine the combination with a frame, a presser and a work support mounted by said frame and being movable one with respect to the other whereby to apply pressure to a series of articles inserted between them, and centering means mounted upon the frame in a location to cause alinement with one another of articles successively inserted between the presser and work support, said centering means including side members adapted to embrace the inserted article and being movable together and apart, a stop engageable by the inserted article and connected to effect movement of the side members when so engaged, and a holder carrying said side members and stop and being demountably secured to the frame to permit removal and substitution of a different centering device.

16. In a press machine the combination of a holder adapted to support a pile of pressed articles, and a presser having an extended pressing surface to bear upon said articles, a part of said presser being retractile while the remainder of it exerts pressure on the articles, whereby to permit passing of a binder around the pile.

17. In a press machine the combination of

- a holder adapted to support a pile of pressed articles, and a presser having an extended pressing surface to bear upon said articles, a part of said presser being retractile while the remainder of it exerts pressure on the articles, whereby to permit passing of a binder around the pile, said retractile part forming one end of the presser and being hinged to the adjacent part whereby to be turned back. 18. In a press machine a presser comprising a plunger, a press plate secured to the end of said plunger transversely thereof and having a pivoted end section adapted to be turned back toward the plunger, and a brace connected to the pivoted section detachably engageable with the plunger when the pivoted section is extended in continuation of the plate. 19. A machine for pressing cemented articles comprising a frame, a work supporting carriage mounted to travel on said frame, a presser movable back and forth toward said carriage substantially in the line of movement thereof, a friction brake device associated with said carriage and with the frame for resisting movement of the carriage and thereby causing pressure to be sustained by the cemented articles from the presser and a signal arranged to be moved under control of the carriage when the latter has reached a given point in its travel. 20. In a press machine a guide having a series of teeth, a carriage movable along said guide, a toothed wheel journaled upon said carriage and meshing with the teeth of the guide, a brake drum connected to said wheel and rotatable thereby, and a brake shoe attached to the carriage and bearing upon said drum to resist movement of the carriage. 21. In a press machine a guide having a series of teeth, a carriage movable along said guide, a toothed wheel journaled upon said carriage and meshing with the teeth of the guide, a brake drum connected to said wheel and rotatable thereby, a brake shoe attached to the carriage and bearing upon said drum to resist movement of the carriage, and means for setting and releasing said brake shoe also carried by the carriage. 22. In a press machine a guide having a series of teeth, a carriage movable along said guide, a toothed wheel journaled upon said carriage and meshing with the teeth of the guide, a brake drum connected to said wheel and rotatable thereby, a brake shoe attached to the carriage and bearing upon said drum to resist movement of the carriage, said brake shoe being a flexible band embracing the drum and anchored at one end upon the carriage, a lever pivoted to the carriage connected to the other end of said band and a manually operable lock device arranged to bear upon said lever and movable to apply pressure to said lever for setting the brake band or to relieve such setting pressure. 23. The combination in a press machine with a work support, a presser, a retainer, and mechanism constructed and timed to operate said presser and retainer in alternation for respectively applying and retaining pressure upon work abutting against the work holder, of a starting and stopping mechanism automatically effective to stop the machine when the retainer is active and the presser is inactive, and means for causing said mechanism to stop the machine at a time when the presser is active and the retainer is inactive. 24. A press machine comprising in combination a work holder, a presser movable toward and away from said work holder, a retainer movable into and out of contact with work pressed upon by the presser, means for operating said presser and retainer in such alternation that the retainer is engaged with the work when the presser is withdrawn, and the retainer is moved away from the work when the presser is forced against it, a start and stop mechanism automatically operable to stop the machine after each cycle when the retainer is engaged with the work and the presser withdrawn, and means associated with said mechanism for causing it to stop the machine at an intermediate point in the cycle when the presser is in contact with the work and the retainer withdrawn. 25. A press machine including pressing means, a stopping and starting mechanism adapted to operate said pressing means through a cycle and then stop, a controller movable to set said stopping and starting means in operation, and means also operable by said controller for stopping the machine at a point before the end of the cycle. 26. A press machine including pressing means, a driver loosely mounted with respect to said machine, a clutch for coupling and uncoupling said driver, respectively with and from the machine, a stop adapted to effect uncoupling of said driver, a controller movable to place said stop in an inoperative position, means tending to place said stop in position for causing uncoupling of the clutch, a mechanism timed with the machine for holding the stop in the inoperative position while the pressing means completes a cycle, and provisions for enabling movement of the controller to place the stop in the uncoupling position prior to the completion of the cycle. 27. A press machine comprising pressing means, a rotatable driver, a rotatable shaft, mechanism through which said shaft operates said pressing means, a clutch adapted to couple said driver to said shaft and to uncouple it, complementary stops for causing uncoupling of the clutch, one of said stops

being carried by the clutch and the other being movable into and out of its path, a controller associated with the last named stop for moving it out of the path of the first stop, means normally tending to return it into such path, an arrester driven with the shaft for holding the second stop in the out position while the driven member makes a complete cycle, and means operable by the controller for shifting the second stop into the in position independently of the arrester.

28. A press machine comprising a presser, a retainer, means for operating said presser and retainer in repeated alternation to press upon a pile of articles and to hold such pile in compressed condition while another article is added thereto; said means comprising a driven shaft, an independently rotatable driver, a clutch for connecting and disconnecting said driver respectively with and from the shaft, a stop abutment rotatable with the clutch adapted when arrested to effect uncoupling thereof, a stop finger movable into and out of the path of said abutment for arresting and releasing the same, a controller connected to said finger movable in one direction to displace the finger from the abutment, a cam driven by said shaft for holding said controller in the finger-displacing position, said finger being jointed, and a fulcrum member arranged to act on said finger between its joint and the abutment when the controller is further moved in the

same direction, whereby to bring the finger into the path of the abutment as a result of such further movement.

29. A press machine designed for progressively adding separate articles, under pressure, to a pile of articles already under pressure, comprising a back-and-forth moving presser, a retainer displaceable transversely of the path of said presser into and out of position to bear on the compressed articles, mechanism for operating said presser and retainer in alternation to bring the retainer into action on the articles, when the presser is out of action, and vice versa, comprising a driven member, a driver, a clutch between the driver and driven member, and a clutch controller, having an abutment, rotatable with the driven member and adapted to be arrested for causing the disconnection of the clutch, a jointed stop finger movable into and out of the path of said abutment, a controller connected with said finger and operable to move it out of said path when operated in one direction, and an arrester for that part of the finger between its joint and its engaging portion adapted to arrest and cause movement of said engaging portion into the path of the abutment with a further movement of the controller in the same direction.

In testimony whereof I have affixed my signature.

FRANK A. BRACKETT.
